Primary Examiner — April Rivas

(57) **CLAIM**

The ornamental design for shipping container door as shown and described.

DESCRIPTION

FIG. 1.1 is a front view of a shipping container door showing my new design;

FIG. 1.2 is a back view thereof;

FIG. 1.3 is a left view thereof;

FIG. 1.4 is a right view thereof;

FIG. 1.5 is a top view thereof;

FIG. 1.6 is a bottom view thereof; and

FIG. 1.7 is a front perspective view thereof.

The broken lines in the drawing figures depict portions of the shipping container door that form no part of the claimed design.
